UNITED STATES PATENT OFFICE.

ROBERT SMITH NOAKES, OF LONDON, ENGLAND.

SUPPORT OR ADJUSTER FOR SOFT COLLARS.

1,133,880.

Specification of Letters Patent. Patented Mar. 30, 1915.

Application filed October 25, 1912. Serial No. 727,744.

To all whom it may concern:

Be it known that I, ROBERT SMITH NOAKES, a subject of the King of England, and resident of London, England, have invented certain new and useful Improvements in Supports or Adjusters for Soft Collars, of which the following is a specification.

The article of manufacture forming the subject of this invention is a support and adjuster for soft collars by the use of which the shape of the outer fold of the collar is continuously retained, while allowing the wearer entire freedom of movement.

This support and adjuster comprises a spring wire of substantially U-shape (the shanks of which are somewhat spaced apart) adapted to be inserted in inverted position between the folds of the collar where its ends overlap and provided at its extremities with stud-like members adapted to be inserted in holes preferably formed at the lower corners of the outer fold of the collar.

In the preferred form of construction the central part of the wire bridging the limbs of the U is curved out of the plane of the limbs to suit the curvature of the neck while the shank portions preferably incline toward one another so that the edges of the collar will be brought near to each other when the stud-like members are in position.

In the accompanying drawings Figure 1 is an elevation and Fig. 2 is a plan of a support and adjuster embodying the invention.

Referring to the drawings, *a, a* denotes the shanks of the support and adjuster; *b, b* are the stud-like members adapted to be

inserted in holes preferably formed in the lower corners of the outer fold of the collar; and *c* is the central portion shown curved to suit the curvature of the neck.

Any movement of the neck of the wearer against the collar merely results in a displacement of the inner fold.

Having described my invention I declare that what I claim and desire to secure by Letters Patent of the United States is:—

1. A unitary device for supporting soft collars comprising two forwardly extending projections adapted to engage the outer fold of the collar, upright members each extending from one of said projections and flaring outwardly therefrom and a single member extending from the upper portions of said upright members and bent downwardly and forwardly therefrom to a central point and serving to maintain the projections in suitable relation to each other. 60

2. A unitary device for supporting soft collars, comprising two forwardly extending projections adapted to engage the outer fold of the collar, flexible upright members each extending from one of said projections 65 and flaring outwardly therefrom and a single member extending from the upper portions of said upright members and bent downwardly and forwardly therefrom to a central point and serving to maintain the 70 projections in proper relation to each other.

In testimony whereof I have signed my name to this specification in the presence of two subscribing witnesses.

ROBERT SMITH NOAKES.
